UNITED STATES PATENT OFFICE.

DANIEL KUNKEL, SR., OF OREGON, MISSOURI.

CAR-COUPING.

SPECIFICATION forming part of Letters Patent No. 276,977, dated May 1, 1883.

Application filed August 31, 1882. (No model.)

To all whom it may concern:

Be it known that I, DANIEL KUNKEL, Sr., of Oregon, in the county of Holt and State of Missouri, have invented a new and Improved 5 Car-Coupling, of which the following is a full, clear, and exact description.

The invention, which is an improvement on the car-coupling for which Letters Patent No. 234,990 were issued to me on November 30, 10 1880, consists in a draw-head provided with an inclined way, up which the coupling-hook slides to catch on a cross-bar at the upper end of the same, and with a stirrup for raising the hook to uncouple the cars.

15 The invention also consists in a shaft provided with an arm, on which the stirrup is hung, which shaft is provided with an additional arm, which rests against a cam-arm on a shaft journaled on the end of the car, which 20 shaft is provided with hand-wheels, a curved arm, or other suitable devices for turning it, whereby the stirrup will be raised.

Reference is to be had to the accompanying drawings, forming part of this specification, in 25 which similar letters of reference indicate corresponding parts in both the figures.

Figure 1 is a perspective view of my improved coupling, showing it attached to a car. Fig. 2 is a longitudinal sectional elevation of 30 the same.

A draw-head, A, of the usual construction, which couples by means of a link and a pin, B, is provided on one side with an upwardly-inclined way, C, at the upper end of which 35 there is a horizontal transverse rod, D, at right angles to the longitudinal axis of the draw-head. The sides *a* are extended above the inclined way, to prevent the pivoted coupling-hook from sliding off the inclined way. A horizontal transverse shaft, E, provided at the 40 ends, which project beyond the sides of the car, with hand-wheels F, is journaled in the draw-head frame adjoining the end of the car. A shaft, G, is journaled in the frame 45 of the draw-head above the upper inner end of the inclined way, and is provided with a crank-arm, H, to the free end of which a stirrup, J, is pivoted, which is provided with a beveled bottom cross-piece, J'. A crank- 50 arm, K, at right angles to the arm H, is mount-

ed rigidly on one end of the shaft G. A crank-arm, L, provided at its outer end with a cam projection, *l*, is rigidly mounted on the shaft E. A curved arm, M, mounted on the crank-arm L, has its free end attached to a rod, O, which extends to the top of the car, or can be connected with a transverse crank-shaft on the end of the car. To that side of the draw-head opposite the one provided with the inclined way a coupling-hook, P, is pivoted, the swinging end of which is beveled. A stop, Q, is provided, upon which the cross-piece J' of the stirrup J can rest, to prevent it from descending too far.

The operation is as follows: If the cars come together, the hooks P slide up the inclined ways C of the opposite draw-heads and catch on the rods D, whereby the cars will be coupled automatically. If the cars are to be uncoupled, the shaft E is turned either by turning hand-wheels F or by swinging the arm M upward, which is accomplished by pulling the rod O upward. Thereby the arm L will be swung upward toward the car, and will press against the arm K and swing the same upward from the car. Thereby the free end of the arm H will be swung upward toward the car and will raise the stirrup J, which raises the free end of the hook and disengages it from the rod D, so that it can be drawn from the inclined way. If the cars are to be prevented from coupling, the stirrup must be held raised.

Having thus fully described my invention, I claim as new and desire to secure by Letters Patent—

1. The combination, with the draw-head A, pivoted hook P, and inclined way C, of the shaft G, journaled in the side of the way, the stirrup J, provided with a beveled bottom cross-piece, J', and means for operating the stirrup, substantially as shown and described.

2. The combination, with the draw-head A, pivoted hook P, inclined way C, the shaft G, and the stirrup J, of the shaft G, the arms H K, shaft E, having an arm, L, and hand-wheels F, substantially as shown and described.

DANIEL KUNKEL, SR.
